UNITED STATES PATENT OFFICE.

ARTHUR McDougall DUCKHAM, OF ASHSTEAD, ENGLAND.

MANUFACTURE OF COKE.

1,289,045.

Specification of Letters Patent. Patented Dec. 24, 1918.

Application filed May 19, 1915. Serial No. 29,145.

To all whom it may concern:

Be it known that I, ARTHUR McDougall DUCKHAM, a subject of the King of Great Britain, residing in Ashstead, Surrey, England, have invented certain new and useful Improvements in the Manufacture of Coke, of which the following is a specification.

While by-product recovery ovens produce a satisfactory metallurgical coke they are costly to maintain and are wasteful of heat, labor and time inasmuch as they are intermittent in operation; furthermore they are not universally applicable as there are only certain coals which can be satisfactorily coked in them without admixture with other coals.

The problem of continuous coking has been solved in the art of making coal gas by use of the now well-known vertical retorts, but the conditions for obtaining the best yield of gas are not those for making coke most suitable for metallurgical and other purposes.

It has been thought that the vertical retort, viewed as a coke oven, would have the advantage that the weight of the column of coal undergoing carbonization would compress the coke during the final stage of carbonization in the lower part of the retort, thus producing a coke of greater density than ordinary gas coke. This expectation has not been fulfilled.

The present invention is based on the observation that the successful production in vertical retorts of coke for metallurgical and other purposes is only to be attained by a process of continuous coking in which mechanical pressure is applied to the top of the charge accompanied by continuous removal of the coke from the bottom of the retort. The pressure must be continuously applied, that is to say, the pressing device must follow the descending charge, being lifted only for the very short period required for admission of fresh coal at the top of the retort.

I have satisfied myself that the relaxation of pressure must be for the minimum possible period, and that it is the coal in the earlier stages of cooking, that is, in the cooler parts of the retort, to which the pressure should be applied, consequently my process differs widely from those in which the pressure at any zone in the retort depends upon the weight of the superincumbent charge, not merely because such pressure is not

variable and would not ordinarily be sufficient for the purpose, but because, if the retort is heated from below upward, the maximum pressure is applied to the hottest part of the charge instead of to the cooler parts.

It is best that the coal should be in a finely subdivided condition.

The pressure applied to the coal should be capable of variation to suit different kinds of coal and the quality of coke required. The order of magnitude of the pressure may be one ton per square foot, but this statement is in no way intended to limit the invention.

The gases and vapors generated during the carbonization are preferably allowed to escape directly from the zones of the retort wherein they are produced, the conditions being such that they carry away as little sensible heat as possible; the arrangement may be suitable for collecting separately the gases and vapors from each zone, or those from all the zones may be collected together.

In the accompanying drawings is shown a retort setting of four retorts, suitable for the invention; Figure 1 is a vertical section on line 1—1 of Fig. 2. The left hand half of Fig. 2 is a horizontal section on line 2—2 of Fig. 1, the right hand half being a like section on line 2'—2' of Fig. 1. The left hand half of Fig. 3 is a vertical section on line 3—3 of Fig. 1 and the right hand half is a like section on line 3'—3' of Fig. 1.

The retorts *a* are of the usual rectangular cross section, the area of which increases downwardly. They are heated by vertical flues *b* in known manner, the heating gases passing upward instead of downward. The combustible gases enter through flues *c* while secondary air enters at *d* and passes around the lower part of the retort in known manner to cool the coke and to become itself pre-heated.

The retort is charged to the level of the foot of the extension *e*. The lower part of the latter constitutes the charging chute of a hopper *f* while the upper part receives a ram *g* operated by means of the piston *h* moving in cylinder *i*. In the position shown the ram *g* has been lifted from its lower position indicated by dotted lines to allow a fresh charge of coal to flow into the extension *e*. Immediately following this flow pressure is again applied to the ram and is maintained while the fresh charge is enter-

ing the retort at a rate fixed by the rate of discharge at the bottom of the retort. In this manner the charge in the retort is kept under constant pressure except for the very short periods during which the ram is being withdrawn and fresh charge is flowing into extension *e*. The hopper *f* is sealed by the rotary feed *f'* at the top and by the rim *g*, so that the retort is gas and air-tight.

10. The general construction of the extension *k* at the lower end of the retort is already known. The curved surface *l* takes the greater part of the weight of the charge and the continuous removal of the coke is by 15 means of an endless traveling band *m* made up of chain links. This particular form of device for removing the charge does not constitute a part of the present invention, it being shown, described, and claimed in Letters Patent No. 1,211,301, granted to me on 20 January 2, 1917.

The hopper *n* into which the coke falls and from which it is periodically discharged by turning the water-sealed door *o*, are well-known.

25. The openings *p* for the escape of volatile products are situated at different levels in the side of the retort and lead directly into a flue *q*. This flue is provided with dampers *r* so that it can be partitioned into chambers which collect the products from the several zones of the retort so that they can be separately withdrawn through off-takes *s*. By removing one or more of the dampers 30 and closing the corresponding off-takes the products may be allowed to mix in the flue *q* to be withdrawn together at say the highest off-take.

Having thus described my invention and 40 the best means I know of carrying the same into practical effect, I claim:—

1. A process of coking coal in a vertical retort, which comprises the application of a mechanical pressure uniformly applied to 45 the upper surface of the coal while under

carbonization at the cooler part of the retort, which pressure is exerted constantly except for the very short period required for the admission of fuel.

2. A process of coking coal in a vertical 50 retort, which comprises the application of a mechanical pressure uniformly applied to the upper surface of the coal while under carbonization at the cooler part of the retort, which pressure is constantly exerted except 55 for the very short period required for the admission of fuel, combined with continuous removal of coke from the bottom of the retort so that the charge continuously travels under pressure through the retort.

3. A process of coking coal in a vertical retort which comprises feeding suitably finely subdivided coal between the surface of the charge in the retort and a ram withdrawn for the purpose and then applying pressure by the ram to this subdivided coal while under carbonization at the cooler part of the retort so as to keep a constant pressure on the charge descending the retort, substantially as described.

4. A process of coking coal in a vertical retort having its hottest zone toward the bottom and a relatively cooler zone toward the top, which comprises feeding finely divided coal to the relatively cooler zone toward the top of the retort, removing coke from the relatively hotter zone toward the bottom of the retort, and applying mechanical pressure uniformly to the upper surface of the coal under carbonization in the cooler zone of 75 the retort, such pressure being exerted constantly except for the very short period required for the admission of coal.

In testimony whereof I have signed my name to this specification in the presence of 80 two subscribing witnesses.

ARTHUR McDougall DUCKHAM.
